Application March 3, 1948, Serial No. 144,893

Term of patent 14 years

(Cl. D48—32)

To all whom it may concern:

Be it known that I, Warren C. King, a citizen
of the United States, residing at Centerville, in
the county of Wayne and State of Indiana, have
invented a new, original, and ornamental Design
for a Combined Tail Light and Reflector for a
Bicycle, of which the following is a specification,
reference being had to the accompanying draw-
ing, forming a part thereof, and in which

Fig. 1 is a bottom plan view of a combined tail
light and reflector for a bicycle showing my new
design.

Fig. 2 is a side elevational view thereof, and
Fig. 3 is a front elevational view.

I claim:
The ornamental design for a combined tail
light and reflector for a bicycle, as shown.
WARREN C. KING.
